UNITED STATES PATENT OFFICE

WILLIAM B. SNOW, OF BOSTON, MASSACHUSETTS, ASSIGNOR TO REVERSIBLE COLLAR COMPANY, OF BOSTON, MASSACHUSETTS, A CORPORATION OF MASSACHUSETTS

DETACHABLE SHIRT BOSOM

Application filed December 22, 1930. Serial No. 503,990.

This invention relates to detachable or false shirt bosom fronts of the so-called "dickey" type and consists in a bosom structure designed to be rendered more adaptable 5 in its capacity to fit and lie smoothly on the person of the wearer with an improved external appearance and resembling in its fit and appearance a bosom which forms an integral part of a full shirt garment.

10 In the illustrated embodiment of the invention the bosom is made from a blank cut from a composite sheet of material. The latter may be formed of a paper or cardboard backing having a measure of inherent stiffness, to 15 the face of which there has been affixed a facing of cotton or other cloth. After the sheet is formed it is subsequently treated to impart a certain measure of flexibility, so that when formed into the completed bosom the 20 latter tends normally to assume a flat and smooth position on the chest of the wearer, but if forced out of its normal flat condition, due to the shape of the wearer to whom it must be fitted, it still preserves a smooth contour without any substantial tendency to 25 buckle, crease or fold, and readily yields to adapt itself to the required contour. The adaptability of the bosom to different shapes of wearers, while still preserving a smooth, 30 pleasing appearance, may be further increased by forming a longitudinal pleat or fold in the bosom as completed, and may be further increased by providing a longitudinal slit or opening within and concealed by 35 the pleat or fold, both of which factors further permit the bosom to yield transversely without, however, destroying its smooth appearance.

This and other objects of the invention will 40 be best understood by reference to the following description when taken in connection with the accompanying illustration of one specific embodiment thereof, while its scope will be more particularly pointed out in the 45 appended claims.

In the drawings:—

Fig. 1 is a front view of a flat blank as it is cut from the composite sheet;

50 Fig. 2 is a front view of the completed bosom formed from the blank sheet in Fig. 1,

having a neckband permanently attached thereto;

Fig. 3 is a side elevation of the completed bosom shown in Fig. 2;

Fig. 4 is a cross section taken transversely 55 through the bosom;

Fig. 5 is a detail showing the neckband;

Fig. 6 is an enlarged detail showing a portion of the bosom front formed from the composite sheet after the latter has been 60 treated, the cloth facing being removed from a portion of the sheet to show the underlying backing; and

Fig. 7 is a section on an enlarged and exaggerated scale, taken on the line 7—7 in 65 Fig. 6, transversely to the scorings or indentations which are formed in the cloth facing and underlying paper backing.

Referring to the drawings and to the illustrative embodiment of the invention, for 70 the composite sheet a backing 11 is employed which I refer to as paper, but is preferably relatively heavy paper or light cardboard. That is to say, the backing should be relatively thin but with a certain measure of inherent stiffness. For this purpose I have found a paper, sold under the trade name of "Index Bristol", well suited. For the cloth facing 13 a plain, medium grade of white unpatterned cotton cloth is preferably selected and the cloth then permanently affixed to the paper sheet with the aid of a starch or other adhesive. This operation may be performed manually or may be carried out in any one of the ordinary coating machines.

The composite sheet thus formed having a paper backing and a plain, unpatterned white cloth facing, is then subjected to an operation which produces on the outer face of the cloth 90 a distinctive pattern but at the same time impresses into the inner or cloth-faced surface of the paper a series of closely arranged indentations, herein in the form of sets of transverse parallel scoring marks. Any suitable pattern may be adopted for this purpose, such as that shown in Fig. 6 (and shown in part in smaller scale on the bosom in Fig. 2), where there is imparted to the cloth facing a series 95 of transverse, parallel depressions 15, these 100

being grouped in longitudinal sets separated each by longitudinal areas 17 or strips without such indentations. The effect of these 5 depressions is to give to the face of the sheet the appearance of having a percale or similar pattern. The pattern, however, is so applied that the depressions forming the pattern in the cloth facing are carried down into the inner or cloth-faced surface of the paper 10 producing corresponding indentations 19, so that the latter, while having a measure of inherent stiffness, thereby has its structure so modified that it is also given a certain measure of flexibility and capacity to bend 15 lengthwise but without the tendency to buckle, crease or fold. This condition is represented in somewhat exaggerated form in Fig. 7, where it will be seen that the depressions 15 produce the effect of scoring the inner face of the underlying backing.

The desired longitudinal flexibility may be imparted to the composite sheet by running the latter between rollers which are forced together under heavy pressure, the roller 20 contacting with the cloth facing having the required raised pattern on its periphery and the companion roller, which engages the outer face of the paper backing, having a smooth surface and causing the raised surfaces on the first roller not only to depress the fabric 25 but to bite down into the backing material and to form similar though somewhat shallower depressions therein.

From a sheet formed in this manner blanks, 30 such as the blank 20 shown in Fig. 1, are cut out by a die or by any other suitable means. In its formation each blank is provided with two longitudinal creases or scorings at 21 and 23, the scoring or crease 23 having an 35 opening in the form of a longitudinal slit 25 of substantial length extending for a portion only of the length of the bosom, herein over the upper mid portion of the blank. The neck portion of the blank is further scored 40 along the curved line 27 and the area between the scoring and the edge of the neck portion is provided with a plurality of inwardly directed slits 29, the neck portion being further 45 cut away at 31 to prevent the forming of a thickened portion at the neckband when the 50 pleat is subsequently formed by folding over the blank.

The blank thus formed, and as shown in Fig. 1, is then creased and folded on the 55 scorings 21 and 23, the right-hand side of the blank being caused to overlap the left-hand side by the distance between the scorings, forming a pleat as shown in Fig. 4, the overlapping portion being pressed flat, causing 60 the slit to lie concealed within the pleat and beneath the overlap, as indicated in Fig. 2.

With the blank in this condition, the slotted 65 areas of the neck portion are bent outwardly and to them is applied a neckband 33, such

as shown in Fig. 5. The latter comprises a composite strip of cloth-faced paper, the latter being preferably of somewhat lighter weight than that from which the material of the bosom is composed. This strip is folded along a central line of scoring and is perforated to form a buttonhole 35. The two sides of the folded neckband strip are placed over the out-turned slotted areas of the neck portion of the bosom to embrace the same and are then permanently secured to those areas and to the bosom, as by stitching, so that, with the neckband thus applied, the bosom is permanently held in its folded or pleated condition, as shown in Figs. 2 and 3. After completion the bosom is perforated at 37 to provide a stud opening.

In its completed condition the main portion of the bosom, including the folded or pleated part, tends normally to assume a substantially flat condition, with the upper portion curving slightly inward due to the drawing or gathering action of the attached neckband. The structure of the bosom, however, provides for imparting a measure of flexibility thereto, longitudinally, due to the presence of the indentations in the underlying backing, and transversely, due to the presence of the pleat and the underlying slit, so that, while normally flat and affording the appearance of a bosom attached to a complete shirt garment, it readily yields without breaking, creasing or buckling to adapt itself to the shape of any wearer.

While I have herein shown and described for illustrative purposes one specific embodiment of the invention, it is to be understood that extensive deviations and departures may be made from the form herein disclosed without departing from the spirit thereof.

Claims:

1. A detachable shirt bosom formed of paper having a cloth facing and having impressed into it a series of closely arranged indentations forming depressions in the cloth facing and the sub-surface of paper thereunder and arranged to impart longitudinal flexibility as well as ornamentation to the bosom, one side of the bosom being folded over the opposite side to form a longitudinal pleat and having an opening or slit extending longitudinally for a portion only of the length of the bosom thereby to impart transverse yieldability to the bosom, the slit being within and concealed by the pleat, and a neckband folded over and permanently secured to the neck portion of the bosom and holding the latter in a substantially flattened, pleated condition.

2. A detachable shirt bosom formed of paper having a cloth facing and having impressed into it a series of closely parallelly arranged indentations forming depressions in the cloth facing and the sub-surface of paper thereunder and imparting a design

and measure of flexibility to the bosom, one side of the bosom being folded over the opposite side to form a longitudinal pleat.

3. A detachable shirt bosom formed of sheet material folded on oppositely directed, spaced, front overlapping and underlapping creases forming a longitudinal pleat, the underlapping crease of said pleat having a longitudinal opening extending for a portion only of the length of the bosom and said pleat having stud openings extending through its overlapping and underlapping folds to receive a stud for preventing unfolding of said pleat or gapping of the longitudinal opening in its underlapping portion,

4. A detachable shirt bosom formed of sheet material folded on oppositely directed, spaced, front overlapping and underlapping creases forming a longitudinal pleat, the underlying crease of said pleat being slit for a portion only of the length of said bosom and said pleat being permanently secured in folded position at its neckband end only.

5. A detachable shirt bosom formed of sheet material folded on oppositely directed, spaced, front overlapping and underlapping creases forming a longitudinal pleat, the underlapping portion of said pleat between said creases being cut away at the neckband end of said pleat to reduce the thickness and stiffness thereof, and a neckband attached to and permanently securing the underlapping and overlapping portions of said bosom adjacent said cut-away portion between said creases.

6. A detachable shirt bosom formed of paper having a cloth facing and having impressed into it a series of substantially parallel closely arranged depressions indenting the cloth facing and the sub-surface of paper thereunder and imparting a design and measure of flexibility to the bosom.

7. A detachable shirt bosom formed of paper having a cloth facing and having impressed into it a series of transversely parallelly arranged depressions indenting the cloth facing and the sub-surface of paper thereunder and imparting a design and measure of longitudinal flexibility to the bosom.

8. A detachable shirt bosom formed of paper having a cloth facing and having impressed into it a series of closely arranged, parallel, elongated depressions indenting the cloth facing and the sub-surface of paper thereunder and imparting a percale-like design and measure of flexibility to the bosom.

In testimony whereof, I have signed my name to this specification.

WILLIAM B. SNOW.
